Specification for Design.

Patented Aug. 25, 1914.

Application filed May 9, 1914. Serial No. 837,590. Term of patent 14 years.

To all whom it may concern:

Be it known that I, SIMON BINSWANGER, a citizen of the United States, residing at St. Joseph, in the county of Buchanan and State of Missouri, have invented a new, original, and ornamental Design for a Broiler-Griddle, of which the following is a specification, reference being had to the accompanying drawing, forming part thereof.

In the said drawing, Figure 1 is a per-

spective view of the broiler-griddle showing my new design. Fig. 2 is a cross section on the line 2—2 of Fig. 1. Fig. 3 is a cross section on the line 3—3 of Fig. 1.

I claim:

The ornamental design for a broiler-griddle, as shown.

SIMON BINSWANGER.
